UNITED STATES PATENT OFFICE.

WILLIAM CODMAN, OF PROVIDENCE, RHODE ISLAND.

DESIGN FOR A SPOON OR SIMILAR ARTICLE.

Application filed January 15, 1924. Serial No. 8,322. Term of patent 7 years.

To all whom it may concern:

Be it known that I, WILLIAM CODMAN, a citizen of the United States, residing at Providence, in the county of Providence and State of Rhode Island, have invented a new, original, and ornamental Design for a Spoon or Similar Article, of which the following is a specification, reference being had to the accompanying drawings, forming part thereof.

I claim:

The ornamental design for a spoon or similar article as shown.

In testimony whereof I have signed my name to this specification in the presence of two subscribing witnesses.

WILLIAM CODMAN.
